UNITED STATES PATENT OFFICE

132,017

DESIGN FOR A FASTENING DEVICE OR SIMILAR ARTICLE

Walter S. Arnstein, Queens, N. Y.

Application February 18, 1942, Serial No. 105,865

Term of patent 3½ years

To all whom it may concern:

Be it known that I, Walter S. Arnstein, a citizen of the United States of America, residing in Queens, county of Queens, State of New York, have invented a new, original, and ornamental Design for a Fastening Device or Similar Article, of which the following is a specification, reference being had to the accompanying drawing, forming part thereof.

Fig. 1 is a plan view of a fastening device or similar article showing my new design.

Fig. 2 is an edge view thereof.

I claim:

The ornamental design for a fastening device or similar article, substantially as shown.

WALTER S. ARNSTEIN.
